Primary Examiner — Derrick Holland*Assistant Examiner* — Lauren Calve(74) *Attorney, Agent, or Firm* — QuickPatents, LLC; Kevin Prince(57) **CLAIM**

I claim the ornamental design for an earring keeper, as shown and described.

DESCRIPTION

FIG. 1 is a front elevational view of an earring keeper, showing my new design, the rear elevational view being a mirror image thereof;

FIG. 2 is a left-side elevational view thereof;

FIG. 3 is a right-side elevational view thereof;

FIG. 4 is a top plan view thereof; and,

FIG. 5 is a bottom plan view thereof.
